UNITED STATES PATENT OFFICE

165,866

COMBINED MILK COOLER AND STAND

Clark E. Rathke, Seattle, Wash.

Application June 12, 1950, Serial No. 10,465

Term of patent 3½ years

(Cl. D23—1)

To all whom it may concern:

Be it known that Clark E. Rathke, a citizen of the United States, residing at Seattle, Washington, has invented a new, original, and ornamental Design for a Combined Milk Cooler and Stand, of which the following is a specification, reference being had to the accompanying drawing, forming a part thereof, in which

Figure 1 is a view in perspective of a combined milk cooler and stand showing my new design, and

Figure 2 is a plan view of the combined milk cooler and stand of Figure 1.

I claim:

The ornamental design for a combined milk cooler and stand, as shown.

CLARK E. RATHKE.
